UNITED STATES PATENT OFFICE.

CHARLES F. ZANZIG, OF MILWAUKEE, WISCONSIN.

SEWING-MACHINE SHUTTLE.

No. 885,824.

Specification of Letters Patent.

Patented April 28, 1908.

Application filed May 23, 1907. Serial No. 375,269.

To all whom it may concern:

Be it known that I, CHARLES F. ZANZIG, a citizen of the United States, and resident of Milwaukee, in the county of Milwaukee and State of Wisconsin, have invented certain new and useful Improvements in Sewing-Machine Shuttles; and I do hereby declare that the following is a full, clear, and exact description thereof.

10 The object of my invention is to provide a simple and effective attachment to sewing-machines for preventing shuttles from skipping, due to wear of a bearing-face of a shuttle, the consequence of which causes the 15 shuttle to become loose in its seat, thereby resulting in imperfect alinement with relation to the machine-needle, so that in the travel of said shuttle it fails to catch the thread delivered thereto by the needle, and thus causes the machine to skip stitches; said 20 invention consisting in certain peculiarities of construction and combination of parts as fully set forth hereinafter with reference to the accompanying drawings and subsequently 25 claimed.

In the drawings: Figure 1 represents a face view of a shuttle-holder, with shuttle and driving-mechanism therefor, having attached thereto a device embodying the features of 30 my invention, the view being partly broken away and in section, as indicated by line 1—1 of Fig. 2; Fig. 2, a top view of the same with the shuttle-holder in section, as indicated by line 2—2 of Fig. 1; Fig. 3, a longitudinal sectional view thereof, as indicated by line 3—3 of Fig. 1, and Fig. 4, a perspective view of my device detached.

Referring by letter to the drawings, A indicates a shuttle-holder or guide having fitted 40 therein a shuttle B of the oscillating type, which shuttle is driven by a spanner C secured to a rock-shaft D in the usual manner. The shuttle-holder or guide is provided with an annular seat a, having a shouldered face b for the reception of the shuttle, a face c of which abuts the shouldered face b of the holder, there being a fragmental ring d engaging the opposite face c' of said shuttle for holding the same in its seat, the ring being 45 held in position on the holder A by dowels e and a clamp f secured to said holder by a screw g as shown. As indicated by the arrows in Figs. 1 and 3, the needle enters the holder adjacent to the face c of the shuttle, the point h of which is adapted to engage the 50 thread and form the loop, which in its for-

mation passes over a segmental web E of said shuttle and is shed therefrom in the usual manner.

Continual oscillation of the shuttle causes 60 wear of the faces c and c', and the lost motion due thereto results in a wobble of said shuttle, which frequently drops away from the line of the needle and fails to catch the thread delivered thereby. To overcome the above 65 defects, due to wear, I provide a clip 1 arranged to be snapped over the hub of the spanner C. The clip is preferably stamped from a single piece of spring-metal, its body-portion 2, which engages the spanner, comprising 70 a shell like sector having elongated tangential fingers 2 adapted to straddle and grip the spanner-arm, thus preventing twisting of said shell on said spanner.

Ears 3 which are bent in from the shell 75 and engage the inner face of the spanner thus prevent the end-thrust of the clip in opposition to tension exerted by a spring-arm 4, which arm projects from said clip and has a conical-head 5 that engages the central portion of 80 the shuttle-web E. The spring-arm 4 consists of a flat leaf-extension forming part of the clip, the arm being bent inward so that its conical head 5 is in axial alinement with the rock-shaft D and also the shuttle, upon 85 which said spring-arm exerts pressure to hold the same to its seat with the least possible friction, owing to its head being concentric with the moving parts.

By the above described arrangement, it 90 will be seen that the face c of the shuttle may wear off indefinitely without effecting the relation of point h thereof to the needle, the spring being always under sufficient tension to hold the shuttle intact, thus increasing the life of a shuttle, which, in practice heretofore, had to be renewed frequently, thereby causing much loss of time and expense. The tension exerted upon the segmental web of the shuttle by the conical 100 head 5, is such that it readily yields to permit passage of the thread between said head and shuttle without affecting the operation of the machine.

While I have shown and described my invention in connection with an oscillating shuttle, it is understood that the same is applicable to any form of shuttle wherein the clip may be attached so that arm 4 be interposed between the shuttle and driving- 105 mechanism therefor to produce the desired result.

While I have shown and described the spring-clip as formed from a single blank, it is obvious that the same may be made in more than one piece, the essential feature 5 being any form of spring provided with means for attachment to the driving-mechanism of a sewing-machine shuttle without previous cutting or fitting, the device being in the form of an attachment that can be ad-10 justed to a machine by simply snapping it in place.

I claim:

1. In a shuttle - mechanism, having a shuttle-guide, a rotary shuttle fitted in the 15 guide, a segmental web extending from the body of the shuttle to a point concentric with the axis thereof, and a drive-shaft for the shuttle concentric with the same; the combination of a flat spring detachably con-20 nected to the drive-shaft, the spring being provided with a conical head concentric with said drive-shaft, and adapted to impinge against the web of the shuttle.

2. In a shuttle - mechanism, having a 25 shuttle-guide, a rotary shuttle fitted in the

guide, a segmental web extending from the body of the shuttle to a point concentric with the axis thereof, and driving mechanism for the shuttle concentric with the same; the combination of a spring-clip detachably connected to the driving-mechanism, said clip being provided with a conical head, adapted to engage the segmental web of the shuttle.

3. In a sewing-machine provided with a 35 rotary shuttle, a guide therefor, and driving mechanism for the shuttle; the combination of a clip carried by the driving-mechanism, said clip being provided with a spring-arm, adapted to impinge the shuttle-center to hold the same against its guide, whereby play of the shuttle in said guide is taken up.

In testimony that I claim the foregoing I have hereunto set my hand at Milwaukee in the county of Milwaukee and State of Wis- 45 consin in the presence of two witnesses.

CHAS. F. ZANZIG.
